LOCKING MEANS FOR RACE HORSE STARTING GATES

Kenneth C. Goodman, Columbus, Ohio

Application October 9, 1942, Serial No. 461,501

2 Claims. (Cl. 119—15.5)

My invention relates to locking means for race horse starting gates. It has to do, more particularly, with locking means which is electrically and hydraulically operated.

In the past, starting gates have been operated by electrical and sometimes mechanical means but these gates have not been very satisfactory in practice. One of the main disadvantages of these prior art gates is that they do not operate satisfactorily at all times. In the prior art electrical gates, it is necessary to make a circuit to the electrically operated lock of each gate in order to release such lock which holds the gates in closed position. It has sometimes happened that the circuit was not made to all of the gate locks and this resulted in one or more of the gates remaining in closed position. As the gates are opened a bell is rung simultaneously to spur the horses forward. When one of the gates does not open and the bell is rung, the horse, in that particular stall, which is trained to "break" at the sound of the bell crashes forward into the closed gate often resulting in injury not only to the horse but to the jockey. In the mechanically operated prior art gates, it is difficult to open all of the gates simultaneously. A further disadvantage of the prior art starting gate is that in the electrical type of lock it has been impossible to release one of the gates independently of the others so as to allow an over anxious horse to "break through" while allowing the other horses to remain in the stalls. This is a marked disadvantage since it is then necessary to get all of the horses back into starting position instead of one if they are all released because of the over-anxious one.

One of the objects of my invention is to provide an electro-hydraulic locking means which will release all of the gates simultaneously.

Another object of my invention is to provide a starting gate wherein each stall gate is provided with a locking means all of which are controlled by a primary electric circuit and which will be operated when the circuit is broken so that there will be no danger of some of the horses being locked in the stalls while the others have been released.

Another object of my invention is to provide a secondary circuit and a switch on the locking means of each individual gate which can be released independently of the others so as to allow an over-anxious horse to "break through" before the race is started.

Another object of my invention is to provide a locking means which is simple in construction and

which can be mounted on the starting gates now in use.

Another object of my invention is to provide a starting gate which can be operated when one of the stall gates is damaged to such an extent that such stall gate cannot be closed but the other stall gates are undamaged.

My invention comprises a race horse starting gate which is mounted on wheels so that it may be moved readily from one place to another on the track. The starting gate has a plurality of stalls which have gates hinged at the front and back ends thereof and in which the horses are placed prior to the starting of the race. I use an electro-magnetic means in combination with a hydraulic means for releasing all of the stall gates simultaneously. Each of the stall gates is provided with a lock which holds the gate in closed position. Each lock consists of a locking pin which is hydraulically operated. All of the locks are connected in a primary circuit which is normally energized in order to hold the locks in locking position. However, when the circuit is broken, all of the locks are simultaneously actuated to release the gates. Thus, it will be apparent that if the gates are in condition for operating when they are closed, there is no danger of their not operating when the circuit to the various locking means is broken. In my device, any of the stall gates can be independently released in order to release any horse which is acting up prior to the start of the race. This is accomplished by means of a secondary circuit and a switch which permits the breaking of the secondary circuit. Breaking the primary circuit to release the gate locks is adapted to make a circuit to an electric bell which rings the moment the stall gates are released. In this type of starting gate, it is practically impossible for a race to get off to a bad start due to the improper operation of the gate.

Various other objects and advantages will be apparent as the description proceeds.

The preferred embodiment of my invention is illustrated in the accompanying drawings wherein similar characters of reference designate corresponding parts and wherein:

Figure 1 is a front elevational view of a starting gate with my locking means associated therewith.

Figure 2 is a top plan view of the structure shown in Figure 1.

Figure 3 is a diagrammatic view of the electrical circuit of my starting gate.

Figure 4 is a side elevation of one of the stall

gates with the electric and hydraulic locking means shown in detail.

Figure 5 is a horizontal sectional view taken along line 5-5 of Figure 4.

Figure 6 is a detail in perspective, partly broken away, of one of the stall gate locking devices and control mechanism.

With reference to the drawings, I illustrate a starting gate represented generally by the numeral 1. The starting gate 1 is shown mounted on wheels 2 and is comprised of an elongated frame structure 3 and of laterally spaced vertical posts 4 and 4a which divide the device into a plurality of stalls. The gate can be moved from place to place by means of a tractor which can be connected to a tongue member 5 (Figure 2) shown at one end of the starting gate. A bell member 6 is disposed in the upper frame structure at the center of the gate.

The stalls formed by the vertical post members 4 and 4a have padded portions 7 running from front to rear to prevent the horses from injuring themselves while waiting for the start of the race. The rear end of each stall has two gate portions 8 which are hinged to the vertical posts 4a. The rear gates 8 are also suitably padded as shown at 8a. The gates 8 are manually locked by suitable means, common in the art, after the horses are positioned in the stalls.

At the front end of each stall a pair of gate members 9 are hinged to the vertical posts 4. The gates 9 have a lower solid panel portion while the upper portion of the gate has wire screen to permit forward vision of the horse and jockey. The lower part of the gate 9 is padded on the inside in the same manner as the sides of the stall and rear gate portions. A strong tension spring 10 is attached to the outside of each gate portion 9, as shown in Figure 5, and to a forwardly extending bracket 10a carried by the post 4. This spring pulls the gate portion open when the lock is released. A pair of catch members 10b are suitably supported by each of the brackets 10a and cooperate with the locking portions 9a carried on the outer panel of the gates 9. This spring catch mechanism 10b prevents the gates rebounding when they are snapped open by the springs 10. The front gate 9 must be well constructed in order to hold the horses in the stall. Vertical reinforcing posts 11 are suitably carried on the outer ends of the gates 9. These posts are welded or otherwise firmly attached to the frame portion of the gate 9. When closed the pair of gates 9 will be disposed in forwardly converging relationship as shown in Figure 2.

The locking means which I use to hold the free forward ends of each pair of gates 9 in closed position comprises a locking pin 12 carried by one of the gates 9, which cooperates with an L-shaped keeper member 13, carried by the other gate member 9. The keeper member 13 has an opening 14 in its horizontal portion through which the locking pin 12 is lifted when the gate is locked. The keeper member 13 is supported by a block 15 which is welded to the vertical post 11 carried on the forward end of the gate 9. The keeper member 13 has a vertical slot 16 formed therein through which passes a bolt 17 which has an adjustable clamping nut 18 threaded on its outer end. It will be seen that loosening the nut 18 the keeper can be moved vertically in order to adjust it relative to the locking pin 12 carried by the other gate member. Guideways 19 are bolted onto the block member 15 to prevent the keeper member 13 from being

jarred out of line the locking pin 12. Thus, each individual pair of gates will have an individual adjustment between the locking pin and its keeper member.

The locking pin 12 is in reality a piston rod carried by the piston 20 disposed in the hydraulic cylinder 21. The cylinder unit 21 is suitably bolted onto the post 11 of the gate 9 directly beneath a U-shaped bracket member 22. The upper end of the rod 12 passes through and is guided in its vertical reciprocation by the U-shaped bracket member 22 which is suitably welded onto the vertical post 11 of the gate 9. The locking pin 12 is provided with a collar member 23. A compression spring 24 surrounds the locking pin 12 above collar 23 and tends to move the pin downwardly. As can be seen from Figure 6, when the gate is in locked position the piston 20, which carries the locking pin, is pushed upwardly by the hydraulic fluid 21a in the cylinder unit 21. This forces the locking pin upwardly into cooperating relationship with the opening 14 in the keeper member 13. The spring 24 is compressed against the upper portion of the bracket member 22. When the fluid 21a is released from the cylinder 21, the piston 20 will be forced downwardly by the spring 24 thus releasing the locking pin 12 from the keeper member 13. When the lock is released as above described, the spring member 10 disposed on the outside of each gate member will instantly snap the gate open, thus allowing the horses to start the race.

A flexible tube or conduit 25 leads from each cylinder 21 to a master piston and cylinder unit 26 which is suitably held in position on the bracket member 10a supported by the post 4. The line 25 is connected to the lower end of the cylinder unit 21 and to the left end of the unit 26. The unit 26 includes a cylinder which has a piston 28 reciprocably mounted therein. A filling plug 26a with an inlet port is disposed on top of the cylinder to allow for replenishing the supply of fluid from time to time. A compression spring 29 tends to push the piston 28 to the right of the cylinder. When the piston is disposed in the right-hand end of the cylinder, the hydraulic fluid fills the cylinder 26 but when the piston is forced to the left against the action of the spring 29 the fluid is forced upwardly through the line 25 and into the cylinder 21 thus holding the locking pin 12 in engagement with the keeper member 13. The piston 28 has a piston rod 30 extending through the end boot 31 to the right of the cylinder member or arm 26. The rod 30 has a clevis 32 threaded on its outer end and is attached to a pivoted rocker arm member 33 by means of a clevis pin 34. The arm 33 is pivotally supported at 35 on a bracket member 36 which is suitably bolted to the underside of the bracket 10a. A strong tension spring member 38 is connected to the lower end of the arm 33 at 37. The other end of the spring 38 is suitably attached to the bracket 39 carried by the bracket 36. An armature 40 is bolted on the upper end of the arm 33. There is a little play between the armature 40 and the arm 33 so that the armature will be free to move slightly to adjust itself.

An E-shaped electro-magnet 41 is suitably supported by an L-shaped bracket member 42 which is suitably bolted onto the member 10a. A brace bar or reinforcing support 42a is provided to strengthen the bracket 42. This magnet 41 is so mounted that the armature 40 will contact it when the upper end of the arm 33 is moved to

the left of Figure 4 against the action of the spring 38. The magnet 41 is connected to a primary electric circuit by suitable means. As shown in Figure 4, the magnet is energized thus holding the arm 33 in vertical position. The piston 28 in the cylinder 26 is forced to the left thus forcing the fluid through the line 25 and into cylinder 21 to hold the locking pin 12 in engagement with the keeper member 13. I provide a secondary circuit in the form of a wire 43 from the magnet 41 to a switch member 44 on each of the magnets of the gates to disconnect them from the primary circuit independently of the others. This allows any one of the gates to be swung open individually by deenergizing the magnet 41 thus releasing the armature 40 which will be pulled to the right by the spring 38 which is connected to the lower end of the arm 33. When this is done the piston 28 will also be moved to the right thus relieving the cylinder 21 of fluid and permitting the spring 24 to move or release the locking pin 12 from the keeper member 13.

Figure 3 shows diagrammatically how the plurality of gates may be operated from a single circuit. In this figure, each of the magnets 41 is connected in parallel across the primary circuit which includes a battery, a relay and a master switch. The signal bell 6 is also connected in parallel across the circuit. The circuit to the magnets on the starting gate is normally closed and the circuit to the bell is normally open. In order to release all of the locking pins from the keeper members, the starter energizes the relay 45, by pressing a button 47, which breaks the circuit to the magnets through a switch member 46 and at the same time closes the circuit to the bell 6. It is to be understood that the master switch must be closed before either the magnets 41 or the bell 6 can be operated. As soon as the starter releases the button 47 which energizes the relay 45, the switch member 46 is sprung back into contact with the circuit to the magnets and is ready for resetting of the gates.

In the operation of my device, the master switch in the primary circuit is closed thus energizing the plurality of magnets carried by the brackets 10a. The stall gates are manually closed and the armatures 40 are moved into contact with the magnets 41 thus forcing the piston 28 to the left in the cylinder 26. This results in the hydraulic fluid forcing the piston member 20 in the cylinder 21 upwardly against the action of the compression spring 24 and carrying the locking pin 12 into its uppermost position. In the event that the keeper member 13 is out of adjustment with the locking pin, it can now be adjusted as shown in Figure 6 to hold the gates in closed position. The horses are placed in the stalls after the front gates 9 are closed. They remain there until the starter is ready to push the button 47 which energizes the relay member 45 and breaks the circuit to the magnets 41 and simultaneously makes the circuit to the bell 6. When the magnet 41 is deenergized, the arm 33 is snapped outwardly or to the right of Figure 4 on its pivot 35 by means of the tension spring member 38. This causes the piston rod 30 to be pulled to the right by the arm member 33 providing a space in cylinder 26 to receive fluid which flows

out of the cylinder 21. The release of fluid from cylinder 21 allows the spring member 24 to force the locking pin downwardly out of engagement with the keeper member 13. The gates are immediately snapped open by means of the spring members 10 which are attached to the outside faces of the gates and to the extending bracket 10a. It will be seen from the above description that I provide a starting gate which has many advantages over the prior art starting gates.

One of the advantages of my invention is that I provide combined electric and hydraulic locking and releasing means for a starting gate which functions to release all of the gates simultaneously.

Another advantage of my invention is that each individual gate can be released separately.

Another advantage of my invention is that I provide a starting gate which is operated by breaking the circuit to the locking means rather than by making it.

Having thus described my invention, what I claim is:

1. A starting gate structure including a frame and comprising a pair of hinged gate members having their free edges connected to one another when in closed position, means for releasably locking said members together, mechanism including hydraulic means supported on the frame structure and in communication with said locking means for normally maintaining the locking means in locked position, an electric circuit and an electro-magnet, the electric circuit and the magnet being effective to maintain the gate members closed and in locked position when energized, means for actuating said locking means at the will of the operator to free said gate members, and means for moving said gate members to open position when the locking means is released, said actuating means being adapted to break the circuit and de-energize the electro-magnet to operate the said mechanism and hydraulic means to permit movement of said locking means to released position and thereby permit opening of said gate members.

2. A starting gate structure comprising a supporting frame and two or more pairs of cooperating gates each of which is hingedly mounted on the frame, the forward free edges of each pair of gates when in closed position being connected to each other, each pair of gates having associated therewith means for opening the gates and an electro-magnet, a hydraulic mechanism mounted on the supporting frame, a latch mechanism secured to the gates, a primary electric circuit for all the electro-magnets, a secondary electric circuit for each electro-magnet, means for opening the primary circuit to de-energize all the electro-magnets, means for operating the hydraulic mechanism when the electro-magnets are de-energized and means for releasing the latching means when the hydraulic mechanism is operated whereby all the gates will be unlatched and opened simultaneously, and means for opening each secondary circuit independently for de-energizing its electro-magnet independently to cause the opening of the pair of gates associated therewith independently of other pairs of gates.

KENNETH C. GOODMAN.
